Attorneys

to the inner combustion sleeve 30, as stated hereinabove, the preferred manner of securing said cover plate to said inner combustion sleeve 30 consists of providing a pair of aligned apertures, one in the cover plate 42 and one in the top plate 36 of the inner combustion chamber, through which apertures extends a bolt 46 having a head portion 48 abutting the cover plate 42 and an externally threaded portion 50 at the end opposite the head to receive a conventional internally threaded nut 52 to engage the threaded portion 50.

To secure the outer casing, the inner combustion sleeve, and the outer combustion sleeve together in a unitary structure, a pair of crossed rods 54 are provided which are secured centrally to each other and which extend through appropriate openings in the side walls of the outer casing, the inner combustion sleeve, and the outer combustion sleeve. Of course, these cross rods may additionally be welded or riveted to the side walls of these members.

In practical operation, the flame from the liquid fuel burner will pass between the walls of the inner and outer combustion sleeves and up through the tapered neck of the outer casing and eventually out through the flame opening 44 and around the cover plate 42. Air will pass up the inner combustion sleeve and out through the apertures provided therein to be admixed with the flame, while air will also be drawn in through the apertures 18 provided in the rim 16 of the outer casing and will be admixed with the flame in the top end of the tapered portion or neck 12. The apertures 22 provided in the outer casing adjacent the tapered neck portion 12 will serve as means for the inlet of cold air and assist in the circulation of air in the outer casing. By providing a cover plate 42 which is larger in diameter than the central opening through which the flame passes, water or any other foreign matter will be prevented from falling into the combustion chambers.

In view of the foregoing description taken in conjunction with the accompanying drawings, it is believed that a clear understanding of the device will be quite apparent to those skilled in this

art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed

10 as new is:

1. A chimney for a liquid fuel burner comprising an outer casing including an upwardly tapered neck portion having a central opening and spaced apertures adjacent the neck portion, an inner and an outer perforated sleeve concentric with said casing, a cover plate of larger diameter than said neck portion secured to the inner sleeve, spaced from said outer casing and overlying said central opening, and means interconnecting said sleeves with said outer casing, said outer casing including an inner perforated flange secured to the bottom thereof.
- 15 2. The combination of claim 1 wherein said means includes crossed rods.
- 20 3. The combination of claim 1 wherein said inner sleeve includes a reduced upper portion and a lowered perforated portion.
